VENTILATOR

James P. Burke, Knoxville, Tenn.

Application October 4, 1937, Serial No. 167,175

7 Claims. (Cl. 98—2)

This invention relates to ventilating means for vehicles such as automobiles, and more particularly to a window construction wherein the ventilating means are formed as a part of the window frame assembly; and has for its object to provide a form of ventilating means which is simple and efficient in both construction and operation and wherein an elongated opening providing for considerable capacity of air flow is effectively shrouded in a manner obviating disadvantages which might ordinarily be expected from such an opening while its air flow characteristics are maintained.

The invention also contemplates the arrangement of baffle or deflector means in a manner directing air flow to meet the desirable requirements and promote ventilating efficiency in the device; the invention further contemplating the arrangement of said baffle means exterior to the window, when used in connection with a window, in such manner that the opening of the window will not be interfered with and will serve as a means of regulating the action of the ventilator.

Still further the invention contemplates the provision of the ventilator having characteristics of form designed to avoid noises or whistling such as is commonly attendant on the use of louvres and similar means heretofore suggested for the ventilating of moving vehicles.

A further object is to provide a horizontally elongated ventilating opening having a cowl or scoop-shaped member extending over one end of said opening and a hood extending therefrom longitudinally above the opening; and still further it is an object of the invention to provide such a construction by the simple cutting away of the lower or underside of a horizontally elongated bulge formed in a vehicle wall, as for instance in the sheeting of a window frame the bulge being cut away on its underside throughout the greater portion of its length.

Still further objects subsidiary to the aforesaid objects, or resulting from the construction or operation of the invention as it may be carried into effect, will become apparent as the said invention is hereinafter further described.

In carrying the said invention into effect I may provide the novel construction and arrangement of parts illustrated, by way of example, in the accompanying drawings, wherein:

Figure 1 is a fragmentary elevation of the upper part of a vehicle door panel embodying the said invention, part of the metal facing being broken away;

Figure 2 is a detail cross section on the same

taken on a plane indicated by the line 2—2 in Figure 1;

Figure 3 is a sectional plan of the same taken on a plane indicated by the line 3—3 in Figure 2;

Figure 4 indicates an enlarged fragment of the side wall of a vehicle or enclosure provided with a modified form of ventilating means including features of this invention;

10 Figure 5 is a plan of underside of the ventilating means of Fig. 4, the wall being shown in section taken on a plane indicated by the line 5—5 in Figure 4; and

Figure 6 is a detail cross section of the same taken on a plane indicated by the line 6—6 in Figure 4.

Figure 7 is a side elevation of a door equipped with a rotatable window and also with another modification of my invention,

20 Figure 8 is a vertical section taken along the line 8—8 of Fig. 7.

Figure 9 is a side elevation of another type of automobile window having a vertical and transversely sliding window in combination with a still further modification of my invention,

Figure 10 is a horizontal section taken along the line 10—10 of Fig. 9, and

Figure 11 is a section similar to Fig. 10 showing a modified arrangement of the screen.

Similar characters of reference indicate similar parts in the several figures of the drawings.

Referring first to Figures 1, 2 and 3. 7 are the usual sash posts of the vehicle door structure, and 8 the top rail, the interior faces of which are provided with suitably formed channels 9 and 10 as guides and sealing means for the vertically adjustable glass window 11, as will readily be understood without further detailed description.

40 The door structure is faced with sheet metal extending at 12 over the posts 7 and also extending at 14 over the face of the top rail 8 and extending materially below the lower edge of the said top rail, as at 15, and terminating in the inwardly turning flange or bead 16, so that when the window is closed the said portions 15 and 16 of the sheet metal member 14 materially overlap the upper marginal portion of the window 11 forming a chamber 17 behind the said portion 15.

45 The metal of the portion 15 is shown as being bulged outwardly, the bulge being of an elongated ovate or so-called streamlined configuration and the under portion of the bulged metal cut away, from one end of the bulge to a point somewhat

remote from the other end thereof, to provide an opening therein above which opening the bulged metal forms a hood 18. One end of this hood extends downwardly in a rounded cowl or deflector 19 defining one end of the said hooded opening.

I prefer to mount, in or over the space in the metal formed by the pressing out of the bulge, a screen 20 of suitable mesh; and it is also proposed to provide in the chamber 17 a baffle plate 21 extending from one end of the said bulge portion inwardly toward the plane of the window and of a length and depth suitable to prevent direct passage of air through the said opening into or from the vehicle, as the case may be, when the window is opened to a sufficient extent to permit any passage of air through the said opening into or from the vehicle.

The bead 16 is also spaced below the lower edge of the said baffle plate, and turning inwardly operates as an air deflector cooperating in promoting the respirating or ventilating functions of the arrangement described.

According to the direction in which the vehicle moves, the cowl 19 operates either to trap and direct air inwardly through the screen to the vehicle or promote a suction causing a flow of air through the screen in the opposite direction as will be well understood, both of which functions serve effectively to insure ventilation in a structure such as of a vehicle which is not completely air tight.

In Figures 4, 5 and 6, 22 indicates any wall of the vehicle such as a side panel in which the bulge 16 may be formed as previously described; in this case the deflector 16 shown in the previous example may be omitted.

In Figures 7 and 8 my invention is illustrated as applied to a door having a vertically movable window section 39 and a window section 40 movable vertically and also rotatable about an axis 23. My invention is adaptable for combination with and will considerably enhance the ventilating qualities of such a window. The window sections 39 and 40 slide vertically in the channel walls 24 and 25 of the sash post 26. The sheet metal facing 27 is formed similarly to that afore-described, being bulged at 28 with the lower or underneath portion 29 thereof being partially cut away and hooded at its front end 30. A screen 31 is inserted interiorly thereof and behind the screen is a deflector 32 which extends from a point slightly forwardly of the hooded end 30 to a point slightly rearwardly of the trailing edge of the bulged portion.

In Figures 9 and 10 my invention is illustrated as applied to a different type of door. In this case the window 33 is movable vertically in its sash 34 for normal sliding motions and when in closed position it may be moved laterally. The bulged portion 35 of the metallic sash covering 36 is placed vertically so that lateral movement of the window uncovers the interior of the vehicle to the chamber 37 and hence to the exterior of the vehicle through the screen 38.

In Figure 10 the screen 38 is illustrated as being in the plane of the main portion of the covering 36 whereas in Fig. 11 the screen 38a is illustrated as being normal thereto, in which case it might preferably be made as a chromium plated grill rather than as a screen.

This invention may be developed within the scope of the following claims without departing from the essential features of the said invention, and it is desired that the specification and draw-

ings be read as being merely illustrative and not in a limiting sense, except as necessitated by the prior art.

What I claim is:

5. In ventilating means for a vehicle having a side window a side wall member depending partially over the window and having a horizontally elongated opening therein located below the upper edge of the window, an outwardly projecting cowl extending vertically over one end of said opening, and an elongated streamlined hood extending horizontally from the top of said cowl longitudinally over the upper part of said opening with its lower edge spaced above the lower edge of said opening.

10. In ventilating means for a vehicle having a side window, a side wall member depending partially over the upper portion of the window and having a horizontally elongated opening therein located below the upper edge of the window, an outwardly projecting cowl extending vertically over one end of said opening, an elongated hood extending horizontally from said cowl longitudinally over the upper part of said opening, and a baffle plate attached at one end to the inside of said wall adjacent one end of the opening and extending inwardly and lengthwise of the vehicle from its point of attachment in the direction of the other end of said opening for a distance approximately equal to the length of the opening.

15. In ventilating means for a vehicle having a side window, a side wall member depending over the upper portion of the window and having an opening therein located in a plane below the upper edge of the window, an outwardly projecting cowl extending vertically over one end of said opening, an elongated hood extending horizontally from said cowl longitudinally over the upper part of said opening, a baffle plate attached to the inside of said wall adjacent the end of the opening remote from the cowl and having a portion extending inwardly of the vehicle from said end of said opening, and said baffle having another portion extending longitudinally a distance at least equal to the length of said opening.

20. In ventilating means for a vehicle having a side window, a side wall member depending over the upper portion of the window and having a horizontally elongated opening therein disposed in a plane below the upper edge of the window, an outwardly projecting cowl extending vertically over one end of said opening, an elongated hood extending horizontally from said cowl and longitudinally over the upper part of said opening, a baffle plate attached to the inside of said wall adjacent one end of the opening and extending inwardly and lengthwise of the vehicle from said end toward the other end of said opening, and a deflector extending horizontally beneath said opening as viewed in side elevation and projecting inwardly of the vehicle as viewed in transverse section.

25. In combination with a side window frame and window of a vehicle, protective sheeting covering said frame, part of said sheeting extending over the upper part of the window opening of said frame in spaced relation to the window, said extension having a horizontally elongated opening therein, an outwardly projecting cowl extending vertically over one end of said elongated opening, an elongated hood extending from said cowl longitudinally over the upper part of said elongated opening, and a baffle plate attached to said sheeting adjacent one end of said

elongated opening and extending inwardly between said sheeting and said window and parallel to said window for the remainder of the length of said opening.

6. In a device in the class described, a ventilator wall having a horizontally elongated bulge projecting outwardly of the wall, said bulge being cut away on its lower portion from one end to a point somewhat remote from the other end thereof to provide, about the opening so formed, a hood extending longitudinally over said opening and a cowl extending around one end of the opening.

7. In a ventilator system for a vehicle having a side window, a sidewall member having an open-

ing therethrough and a portion adjacent the opening bent to form a hood extending completely over the opening in a lengthwise direction and a cowl extending completely around one end of the opening, and a baffle extending from the sidewall member at a point rearwardly of the opening inwardly of the vehicle and forwardly of the vehicle parallel with said sidewalls and having a length equal at least to the length of said opening whereby the leading edge of said baffle extends forwardly of said cowl, said sidewall member extending below the upper edge of said window and having said opening formed therein in a plane below the upper edge of the window.

JAMES P. BURKE
